UNITED STATES PATENT OFFICE.

JOSEPH MAURICE TRENEER, OF NEW YORK, N. Y., AND CHARLES S. BENJAMIN, OF EAST ORANGE, NEW JERSEY, ASSIGNEES TO ANDREW J. DOREMUS, OF WEST NEW BRIGHTON, NEW YORK, AND HOWARD G. TURNER, OF PATERSON, NEW JERSEY.

METHOD FOR THE PURIFICATION OF HYDROCARBONS.

1,392,370.

Specification of Letters Patent.

Patented Oct. 4, 1921.

No Drawing.

Application filed June 4, 1920. Serial No. 386,632.

To all whom it may concern:

Be it known that we, JOSEPH MAURICE TRENEER, a citizen of Great Britain, and CHARLES S. BENJAMIN, a citizen of the 5 United States, residing in, respectively, West New Brighton, county of Richmond, city of New York, and State of New York, and East Orange, county of Essex, and State of New Jersey, have invented certain 10 new and useful Improvements in Methods for the Purification of Hydrocarbons, of which the following is a full, clear, and exact specification.

Our invention relates to methods for 15 purifying hydrocarbons and refers particularly to methods for purifying petroleum hydrocarbons.

Crude petroleum hydrocarbons, and especially those hydrocarbons which are solid, 20 semi-solid or non-liquid at ordinary temperatures, contain unsaturated hydrocarbons, oils, water and other ingredients which it is necessary to eliminate in order to obtain products which are practically 25 colorless, odorless and tasteless.

This conversion of the crude product into the practically pure commercial article must be performed with considerable care in order that the desirable compounds may not 30 be disintegrated, or broken down, into undesirable ones, and, for this reason, the proposed use of many chemicals and the following of many suggested processes have proven to be practically useless.

It is essential, therefore, that an efficient process for the described purification must be one which will destroy, or remove, the deleterious substances without affecting the properties of the desirable hydrocarbons.

The use of strong chemicals is objectionable on account of their liability to attack the hydrocarbons and the employment of extremes of temperatures are similarly to be avoided as many of the hydrocarbons are 45 affected, or changed, by abnormally high, or abnormally low, temperature and are particularly sensitive to chemical reagents under these circumstances. It is therefore evident that the use of chemicals under 50 conditions that require extreme temperatures, or pressures, are not as desirable as a process conducted under normal conditions.

It is further to be noted that the com-

monly employed practice of sweating steaming and filter pressing is cumbersome, requires the use of expensive machinery, necessitates the employment of a very considerable amount of labor and requires a great amount of time for the following out of the operations.

The element of cost is also an essential consideration, and hence, the use of volatile solvents, or of volatile active reagents, must be accompanied by conditions that will not allow of excessive loss.

The process of our invention overcomes all of the above suggested difficulties and presents a method whereby crude hydrocarbons may be purified at a minimum of cost and without the danger incident to the 70 employment of strong acids, or extremes of temperatures.

We have discovered that crude hydrocarbons, and especially those which are solid, or semi-solid, at ordinary temperatures, may be efficiently and economically purified by treating them with a solution of sulfur-dioxide in certain solvents. We have further found that such treatment does not require the employment of extreme temperatures or the use of pressure.

As a solvent means, we prefer those chemicals which will dissolve the objectionable compounds incorporated in the hydrocarbons as well as the objectionable ones 85 which are formed by the action of the sulfur-dioxide, thus allowing of the ready separation of the desired hydrocarbons from those which it is advantageous to remove.

We have further found that our process is particularly advantageous in its application to those solid and semi-solid hydrocarbons known commercially as paraffins, vaselines, petrolatums and similar substances, although we do not limit ourselves 95 to such particular applications.

While our process may be employed with solid hydrocarbons, such as paraffin, in lumps of considerable size, we prefer to use the solid hydrocarbon in a finely comminuted condition as more effective results are thus produced.

We give the following example of the following out of the process of our invention:

Sulfur-dioxide gas is run into 12 gallons

benzol until 8 pounds of the gas are absorbed. This solution is then added to 100 pounds finely comminuted yellow crude scale paraffin wax and the mixture thoroughly agitated until a test of the paraffin shows desired purification. This operation may be performed at the ordinary room temperature, that is, about 20° C. without pressure and usually requires but a few moments for its completion. The solution is then separated, as by filtration, and the remaining solution removed from the paraffin by pressure, heat or other suitable means.

15 Any remaining coloring matter may be substantially removed from the paraffin by passing it in a melted condition through a bed, or filter, of charcoal, infusorial earth, or similar acting material. The benzol 20 may be recovered from the dissolved hydrocarbons and other substances by distillation, or other suitable means, and be reused for further purification processes, or the benzol solution may be reused without 25 purification if its contamination is not too great. The sulfur-dioxid in gaseous state follows the cycle of the benzol during the recovery by distillation and is redissolved in the purified recovered benzol without 30 considerable loss.

The benzol in the above example may be substituted by acetone, ethyl alcohol, wood alcohol, toluene, xylene, carbon-tetrachlorid, chlor-benzol, dichlor-benzol, or by any other 35 alcohol or other solvent having properties making it adaptable to our process.

While we have mentioned a temperature of 20° C. in our example, we do not limit ourselves to this particular temperature, 40 which may be varied to suit the manufacturing conditions or particular grade of crude paraffin employed and we prefer to use a temperature above 32° F.

In the example we produce the solution 45 of sulfur-dioxid by passing sulfur-dioxid gas through the solvent, but any other means of producing such a solution may be employed.

By the following of our process, as above 50 described, the deleterious unsaturated hydrocarbons and oils, the coloring matters and the water are practically removed leaving the paraffin practically odorless, colorless and tasteless and with higher melting point 55 than that of the original crude paraffin.

It is evident from the above that our process presents a new, novel and useful method for the efficient, economical and easy purification of hydrocarbons.

60 We do not limit ourselves to the particular chemicals, quantities, temperatures or mode of procedure as described, all of which may

be varied without going beyond the scope of our invention as described and claimed. What we claim is:—

65

1. A process for the purification of non-liquid hydrocarbons which comprises treating the impure hydrocarbons with benzol containing sulfur-dioxid and separating the non-liquid hydrocarbons from the liquid 70 impurities.

2. A process for the purification of paraffin which comprises treating impure paraffin with benzol containing sulfur-dioxid and separating the paraffin from the liquid im- 75 purities.

3. A process for the purification of non-liquid hydrocarbons which comprises treating the impure hydrocarbons with benzol containing sulfur-dioxid at atmospheric 80 pressure and separating the non-liquid hydrocarbons from the liquid impurities.

4. A process for the purification of paraffin which comprises treating impure paraffin with benzol containing sulfur-dioxid at 85 atmospheric pressure and separating the paraffin from the liquid impurities.

5. A process for the purification of non-liquid hydrocarbons which comprises treating the impure hydrocarbons with a solution of sulfur-dioxid in a solvent capable of 90 dissolving the original objectionable compounds and those formed by the sulfur-dioxid at atmospheric pressure and at a temperature above 32° F. and separating 95 the non-liquid hydrocarbons from the liquid impurities.

6. A process for the purification of paraffin which comprises treating impure paraffin with a solution of sulfur-dioxid in a 100 solvent capable of dissolving the original objectionable compounds and those formed by the sulfur-dioxid at atmospheric pressure and at a temperature above 32° F. and separating the paraffin from the liquid im- 105 purities.

7. A process for the purification of non-liquid hydrocarbons which comprises treating the impure hydrocarbons with benzol containing sulfur-dioxid at atmospheric 110 pressure and at a temperature above 32° F. and separating the non-liquid hydrocarbons from the liquid impurities.

8. A process for the purification of paraffin which comprises treating impure paraffin with benzol containing sulfur-dioxid at atmospheric pressure and at a temperature above 32° F. and separating the paraffin from the liquid impurities.

Signed at New York city, in the county 120 of New York and State of New York, this 2nd day of June, 1920.

JOSEPH MAURICE TRENEER.
CHARLES S. BENJAMIN.
